Primary Examiner — Christy Nemeth(74) *Attorney, Agent, or Firm* — KA Filing LLC; Wayne V. Harper; Cynthia Ward Flanigan(57) **CLAIM**

The ornamental design for a battery box, as shown and described.

DESCRIPTION

FIG. 1 is a top front perspective view of a battery box showing my new design;

FIG. 2 is a bottom rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof on an enlarged scale;

FIG. 8 is a bottom plan view thereof on an enlarged scale; and,

FIG. 9 is an enlarged view of part 9 in FIG. 1.

The dash-dash broken lines in the drawings are for the purpose of illustrating portions of the article that form no part of the claimed design. The dash-dot broken lines in FIGS. 1 and 9 are for the purpose of illustrating the boundaries of the enlarged fragment shown in FIG. 9 and form no part of the claimed design.
